UNITED STATES PATENT OFFICE.

ROBERT B. HUGUNIN, OF HARTFORD, CONNECTICUT.

SASH-FASTENER.

SPECIFICATION forming part of Letters Patent No. 608,606, dated August 9, 1898.

Application filed April 5, 1898. Serial No. 676,555. (No model.)

To all whom it may concern:

Be it known that I, ROBERT B. HUGUNIN, a citizen of the United States, residing at Hartford, in the county of Hartford and State of Connecticut, have invented a new and useful Sash-Fastener, of which the following is a specification.

My invention relates to improvements in sash-fasteners having a central or side fastening-tongue and operated in connection with a face-plate.

The objects of my invention are, first, by strengthening of face-plate through wall of shell to enable employment in opening in shell and plate of full width of plate to wall of shell for admission of fastening-tongue body and fastening-tongue within a minimum width of plate, rendering fastener in width of plate applicable for thin sash, (see Figs. 1 and 4;) second, through opening in plate to wall of shell enable application of body of fastening-tongue with central or side fastening-tongue to same plate, (see Figs. 2 and 3; same un-assembled, see Figs. 4, 5, 6, and 7;) third, through employment of inner surface in opening in shell and plate as bearings, with correspondingly-constructed bearings on body of fastening-tongue and in connection with outside bearings on same and shell, obtain efficient holding and working bearings for body of fastener-tongue movably confined in opening and operated through handle of same and spring, (see Figs. 1, 8, 9, 10, 11, and 12;) fourth, to unite in a-tongue sash-fastener operated in conjunction with a face-plate a spring holding-disk having a side edge bearing-flange conforming with rear opening in shell and bearing on sides of same to securely hold the spring within center of shell-opening. (See Figs. 1 and 7.)

My invention further relates to improvements in sash-fasteners having a fastening-tongue and operated in connection with a face-plate, the objects of my improvements being to unite with sash-fastening plates having a resisting or butting end or ends, against which the tongue of the fastener operates, a butting flange or flanges on rear side of butting end or ends of the plate, the flanges resting against the wood at end or ends of the tongue mortise or mortises made on the edge of sash, and through which the plate is greatly

assisted in resisting pressure and shock at the point same occurs in work required of plate, and to the preventing of loosening, as from screw-fastening alone. This butting flange is shown applied to the single butting-end required in the short plate limiting the movement of sash to support when opened, (see Fig. 13,) and not shown, though applicable on the four butting ends of plate located on each side of locking and locking ventilating-slots O O', preventing movement of sash in either direction. (See Fig. 14.)

My invention further relates to improvements in sash-fasteners having a fastening-tongue operated in conjunction with a face-plate, the objects of my improvements being to unite with sash-fasteners a sash-steadying pressure-spring H, applied at top of and in rear sash-channel, acting when rear sash is closed (see Fig. 16) to hold that edge from sagging open at the top, the opposite edge being firmly held by the fastener, and also to preserve the level of the meeting-rails between the sash. The lower sash resting on the window-sill when closed is not affected from sagging.

I attain these objects by the mechanism illustrated in the accompanying drawings, in which—

Figure 1 is a sectional view showing the features of my invention—to wit, face-plate A, shell A', wall of shell A'', fastening-tongue body B, handle B', central fastening-tongue B'', bearing-disk b, spring-disk b', having spring-seat d, opening C C', extending through shell and plate, bearings on shell c c' for bearings b'', coiled spring D, and spring-disk E, having side flange e and preferably spring-seat d' and securing-rivet f. Figs. 2 and 3 are perspective views showing application to same face-plate of central B'' and side fastening-tongue B'''. Fig. 4 is a rear plan view of plate A, showing shell A', and wall of shell A'', and bearings c c' for bearings b'', and opening C C'. Figs. 5 and 6 are plan views showing central B'' and side fastening-tongue B''' as located on fastening-tongue body. Fig. 7 is a plan view of coiled spring D and spring-disk E, having side flange e and preferably spring-seat d' and rivet f. Figs. 8, 9, 10, 11, and 12 are views of modifications in fastener-bearings b''' and c'', adapted to application of side

tongue B''' only, (see Figs. 8 and 9,) and bearings S and b''' with opening C C' straight from edge of plate to wall of shell for either form of tongue B'' or B''' , the bearing spring-disk 5 b' being employed in each. Figs. 13 and 14 are views of sash-fastening butting plates F' F , showing general application through plate F' of butting flange n to butting ends of the plates. Fig. 15 is a plan view of a sash pressure 10 and steadyng spring H . Fig. 16 is a view showing steadyng and pressure spring H applied to upper end of rear channel. Fig. 17 is a right-hand middle section of a sash-frame, showing fasteners applied to front 15 and rear sash-channels with reference to the meeting-rails when the sash are closed. Figs. 18 and 19 are edge views of both sash turned edge out from frame, (see Fig. 17,) showing fasteners applied to the frame and fastener-plates correspondingly applied to the edge of 20 the sash with reference to the tongues of the fasteners when sash are closed.

A is a face-plate; a a' a'' , longitudinal and transverse centers of plate and shell.

25 A' is an open shell on rear side of face-plate, having a central C and side opening C' , extending through the plate for the admission and working support of body of fastener and fastening-tongue in connection with bearings c c' on shell at each side of opening C' ; A'' , wall of shell A' on rear side of plate A , the strengthening from which through depth of metal in the wall permitting the construction of plate 30 with opening C C' extending to wall across the plate without impairment of transverse strength, (see Fig. 4;) B , body of fastener, having handle B' , central B'' or side fastening-tongue B''' , bearing-disk b , spring and bearing disk b' , (these disks b and b' are 35 united to save metal between them and lessen the weight of the fastener,) and bearings b'' for bearings c c' on the shell. (See Figs. 5 and 6.) (For modifications in construction of bearings see Figs. 9 and 11.)

45 C is the central opening in the shell A' , preferably round and tapered and extended through plate.

50 C' is the side opening in shell A' , extending between C and the edge of the plate; C C' , combined opening in shell and plate for the admission, working, and guidance of bearings 55 on body of fastener B and fastening-tongue B'' or B''' , spring D , and spring flanged disk E . (See Fig. 1.)

55 With wall of the shell located at rear edge of the plate the transverse strength is maintained while employing the entire width of same for opening to the wall for admittance of working parts of fastener, obtaining there- 60 by a minimum width of plate and adaptation of fastener to employment of a central or side fastening-tongue and to application in channels in the frame for thin sash.

65 The modifications (see Figs. 8 and 9) with bearings b''' and c''' on the sides of opening through wall of shell necessitate leaving the plate solid in place of opening C to maintain

transverse strength, limiting fastener to side tongue only. Other modifications (see Figs. 10, 11, and 12) admit both forms of tongue to 70 same plate and with which the opening C C' is of uniform width. The sides of the bearing-disk b are removed, leaving end, as bearing b''' and bearing S are constructed on the sides of fastener-body, conforming with opening in 75 shell in place of the removed sides. It will be observed with these modifications the essential features of my invention are retained.

D is a coiled spring, confined in opening C between spring bearing-disk b' and flanged 80 disk E and secured by rivet f or equivalent and through which the fastening-tongue is operated.

E is a flanged spring-disk having, preferably, spring-seat d' . The flange e around one 85 side at the edge is of sufficient depth to steady same as bearing on side of opening C in shell. This disk is preferably made of thin metal (see Figs. 1 and 7) to save space between the fastening-rivet f and spring D in opening in 90 the shell.

F' F are sash-fastening plates employed in forms shown in Figs. 13 and 14 in connection with tongue sash-fasteners, each having butting flange or flanges n . The plates are applied as shown in Figs. 18 and 19. A mortise is made in the edge of the sash conforming to the plate applied in the center of or at the side of the edge of the sash, according to employment of central or side fastening tongue-fastener. Fig. 18 shows application of plates for central tongue-fastener applied on the right side in the rear sash-channel of the frame, Fig. 17, and Fig. 19 shows application of same plate for side tongue-fastener applied 100 on right side in front sash-channel of the frame, Fig. 17, Figs. 18 and 19 representing the relative position of the sash when closed, as shown by the dotted lines projected across between these figures and Fig. 17. The two-slot form Fig. 14 is a locking and 110 ventilating plate by means of which the sash are locked when closed and opened for ventilation. The plate shown, Fig. 13, with butting flange, is employed with the fastener 115 for sash-holding purposes and to lock the sash by reversing butting end of plate in application when closed. Several of these holding-plates are applied to the edge of the sash.

120 n is a butting flange extending below and across the base at the butting end or ends of the sash-plate, of a depth to furnish a firm butting resistance against the wood at end of mortise made for the tongue of the fastener 125 on the edge of the sash, preventing pressure and shock in the work of the plate from loosening same from screw-fastening.

H is a sash-steadying pressure-spring applied at the top of and in the rear sash-channel and acting only when the sash is closed at the top to hold that edge from sagging open at the top, the opposite edge of the sash being held up by the tongue of the fastener.

The lower sash resting on the window-sill when closed remains firm. The form of the spring for this work is not essential so the side pressure is furnished the rear sash at the closing-point.

5 K is the lower sash; L, upper sash; K', lower sash-channel; L', upper sash-channel; M, middle section, right side of sash-frame, Fig. 17; M', upper section, left side of frame, Fig. 16; P N, meeting-rails of sash K L, Figs. 17, 18, and 19; R, sash division-strip; r, front stop, and r' rear stop in frame.

The fasteners are applied to the sash-channels on either of the frames, one for each sash. 15 Fig. 17 shows the fasteners applied to the sash-channels on the right side, and Figs. 18 and 19 show the fastening-plates correspondingly applied to the edge of the sash with reference to the tongues of the fasteners as when 20 the sash are closed. (Shown by the dotted lines projected from these points in the frame to the edges of the sash.) Fig. 17 shows fasteners applied having central and side fastening-tongues, the upper the central and the 25 lower the side tongue, and the sash for each. Figs. 18 and 19 show the position of the fastening-plates for each form of tongue. With the central the fastening-plates are applied near the center of the edge, and for side tongue 30 near the edge of the edge of the sash. The form of plate shown in Fig. 14, having two slots on the edge, is applied to the sash to engage the locking-slot when closed and the other slot when opened for ventilation. The 35 steady pressure-spring H employed with fastener for rear sash is applied to the frame at top of rear sash-channel, acting on the sash edge at the point of closing, that the friction from same be the least possible, and in- 40 stantly released on opening the sash, the pressure from the spring holding that edge from

settling open at the top, the opposite lower edge being firmly held by the tongue of the fastener, this steadyng of upper sash preserving level of meeting-rails between the 45 sash. The lower sash resting on the window-sill requires no such support.

What I claim as my invention is—

1. In a sash-fastener employing a face-plate and rear shell with an opening through same, 50 and side of same, and face-plate in combination with body of fastener secured and working in the shell-opening, having a fastening-tongue working in and through the opening in the face-plate for same, spring and bearing disk, and bearing-surfaces corresponding with surfaces in opening and on the shell as bearings and provided with a spring, and operated through a handle, substantially as, and for the purposes set forth. 60

2. In a sash-fastener having a face-plate and rear shell, with opening extending through same and plate, in which are confined a fastening-tongue, body of fastener, and spring, operated through a handle, in combination 65 with a spring holding-disk provided with a side flange, substantially as, and for the purposes set forth.

3. In combination with the upper sash of a window, a fastener provided with a tongue 70 engaging the lower end of one edge of the sash, a spring pressure-plate H secured to the upper end of the window-frame and adapted to engage the upper opposite edge of the sash when the latter is raised to its normal closed position, whereby sagging of the sash is prevented, as specified. 75
